OPERATING MECHANISM FOR ELECTRIC SWITCHES

George J. Meuer, Milwaukee, Wis., assignor to Cutler-Hammer, Inc., Milwaukee, Wis., a corporation of Delaware

Application March 17, 1941, Serial No. 383,667

9 Claims. (Cl. 200—5)

This invention relates to improvements in operating mechanisms for electric switches.

A primary object of the invention is to provide novel mechanical interlocking means for the operating elements of switches, involving the use of three pushbutton control elements to provide "forward," "stop" and "reverse" control functions for an electric motor or the like, or to provide "slow" or "fast" speed or "stop" control functions as a starting and stopping control station for a two-speed motor.

Another object is to provide for attainment of the aforementioned and other control functions by use of switches of substantially standard form, but modified in respect of the operating elements thereof to be associated with the novel operating and interlocking elements of the control station as a whole.

Another object is to provide a novel control station of the three pushbutton type.

Another object is to provide a pushbutton control station having interlocking means for latching the switch parts in any one of a number of different circuit controlling positions.

Another object is to provide novel means for supporting and enclosing the switches and their associated operating mechanism to provide the control station.

Another object is to provide a switch interlocking mechanism the parts of which are of simple and inexpensive form whereby formation and assembly of said parts is facilitated.

Other objects and advantages of the invention will hereinafter appear.

The accompanying drawings illustrate certain embodiments of the invention which will now be described, it being understood that the embodiments illustrated are susceptible of modification in respect of certain structural details thereof without departing from the scope of the appended claims.

In the drawings,

Figure 1 is a vertical sectional view of a two-speed, across-the-line, manual starter for an alternating current motor, the insulating base and cover elements of one of the two multi-pole, slow-break switches being shown in elevation, and both switches of the pushbutton station being shown in their normal circuit interrupting positions.

Fig. 2 is a fragmentary view, partly in section, similar to Fig. 1, but showing the left-hand pushbutton depressed and latched to effect circuit closing operation of its associated switch, the manner in which the right-hand pushbutton is

restrained against depression thereof, pending momentary depression of the intermediate pushbutton, being likewise illustrated.

Fig. 3 is a fragmentary horizontal sectional view, on the line 3—3 of Fig. 1, one of the pushbuttons and its associated stop member being shown in dotted lines, to illustrate the form of the latter.

Fig. 4 is a fragmentary view, partly in elevation and partly in section on the line 4—4 of Fig. 1.

Fig. 5 is a perspective view, in separated relation, of certain of the interlocking and latching elements shown in Figs. 1 to 4, a fragment of the shank portion of the intermediate pushbutton being also illustrated.

Fig. 6 is a fragmentary view, partly in vertical section and partly in side elevation, quite similar to Fig. 1, but illustrating a slightly modified form 20 of my improved operating and interlocking mechanism adapted to use with a pair of double-pole, single throw switches of the snap action type, both of the switches being shown in the "off" positions to which they are normally biased by 25 parts of the interlocking mechanism.

Fig. 7 is a view in side elevation, quite similar to Fig. 6, but showing the right-hand pushbutton depressed and latched to retain its associated switch in circuit completing position, a fragment of the casing cover being shown in section.

Fig. 8 is a detail perspective view of one of the two latch bars employed in the control station of Figs. 6 and 7.

Fig. 8^a is a fragmentary vertical sectional view 35 of a slightly modified form of the device illustrated in Figs. 6, 7 and 8.

Fig. 9 is a detail perspective view of one of the two combination interlocking and latching bars 40 employed in the control station of Figs. 10 to 12, inclusive.

Fig. 10 is a view partly in side elevation and partly in vertical section illustrating a three 45 pushbutton control station employing a pair of multi-pole switches, each of which is of the double throw type without an "off" position, all of the pushbuttons being shown in their upper extreme positions.

Fig. 11 is a fragmentary elevational view of the 50 device shown in Fig. 10, but showing the relative positions of certain of the switch parts and of the interlocking and latching elements associated therewith upon depression of the left-hand pushbutton, and

Fig. 12 is a fragmentary vertical sectional view, on the line 12—12 of Fig. 10.

Referring first to the pushbutton station shown in Figs. 1 to 5, the numeral 15 designates the lower or main body portion of an enclosing casing, which is preferably formed or fabricated from sheet metal to elongated substantially rectangular or box-like contour. A closure or cover member 16, which is likewise preferably formed of sheet metal, has a downwardly extending flange or skirt 16^a which peripherally surrounds the upper end of the casing portion 15. Rigidly attached to the opposite ends walls 15^a and 15^b of portion 15 are lugs or brackets 15^c and 15^d which are respectively provided with tapped openings to receive the shanks of a pair of screws 17, 17 whereby the cover member 16 is removably secured to portion 15. The casing illustrated is of the surface mounting type, and accordingly the bottom wall 15^e of portion 15 is preferably provided at suitably spaced points with a plurality of openings (not shown) to provide clearance for the shanks of screws for attachment of the casing to any suitable support. The aforementioned end walls 15^a and 15^b are provided with suitable knockouts, such as 15^f and 15^g, which upon removal afford openings for entry and exit of a suitable cable or wires for proper electrical connection with the various terminals of the switch mechanism.

Permanently attached to the inner surface of cover member 16, as by means of a pair of metal eyelets 18, 18 is a yoke member or bracket 19 which is provided with a flat portion 19^a which is located in a plane parallel to and spaced inwardly from the cover member 16. Portion 19^a is preferably provided at opposite edges thereof with upwardly angled ribs or flanges 19^b and 19^c, which are adapted to strengthen portion 19^a and to resist bending thereof in a transverse plane.

The switches employed in the control station of Figs. 1 to 5 are of the slow-break type adapted for the control of alternating current circuits, said switches as shown being of the character disclosed in Patent No. 2,133,545, granted Oct. 18, 1938, to A. W. Krieger, and assigned to Cutler-Hammer, Inc., the assignee of the present application. As best illustrated at the left-hand side of Fig. 1 and in Fig. 4 hereof, said switches are of the three-pole type shown in Figs. 17 to 19 of said Patent No. 2,133,545. More specifically, each of the two like switches 20, 20 comprises a main insulating base portion 20^a which is provided with a recess 20^b opening to the upper surface thereof (Fig. 1), said recess being provided with two pairs of longitudinally aligned barrier portions (such as shown at 20^c and 20^d) to provide three pairs of longitudinally aligned auxiliary recesses. Said auxiliary recesses are respectively provided with ledges offset inwardly and located in a common plane a substantial distance from the upper surface of base 20^a. Positioned upon each ledge is a flat contact plate 21, each of the plates 21 preferably having rigidly attached to the lower surface of its free end portion, as by spot-welding, a contact tip 21^a of coin silver, or other high quality contact material. Plates 21 are rigidly secured in their respective positions by hollow metal members 22 whose shank ends are upset over said plates, as shown at 22^a, 22^b, the flat heads 22^b of which are of square or other polygonal contour to seat in correspondingly shaped recesses in the lower surface of base 20^a, whereby the same act as wiring terminal members, in conjunction with

the usual binding screws 23, which provide for bottom wiring of the switch mechanism.

Associated with and underlying each pair of longitudinally aligned contact plates 21 is a bridging contactor 24 having attached to each end at the upper surface thereof the pair of contact tips 24^a, 24^b, formed of coin silver or the like, for cooperation with the respective pairs of contact tips 21^a, 21^b aforementioned. Each of the three bridging contactors 24 for each switch (only one of which contactors is shown in Fig. 1) is normally biased upwardly, as by means of a coiled compression spring 25 individual thereto, to effect engagement of the contact tips 24^a, 24^b with the tips 21^a, 21^b of the respective pair of stationary contacts associated therewith.

A molded insulating plunger 26, of the form shown in detail in Fig. 18 of said Patent No. 2,133,545, is adapted to seat against the upper surfaces of the three contactors 24 for support by the latter, the springs 25 tending to effect extreme upward movement of contactors 24, with consequent upward movement of plunger 26. Rotatable within a cavity 26^a at the upper end of plunger 26 is a disk or cylinder 27, said cylinder being supported for rotation by a pin 28, which seats downwardly within a pair of open pivotal bearings (not shown) formed in said plunger. The length of pin 28 and the form of plunger 26 are such that accidental lateral disassembly of the pin from cylinder 27 is positively prevented. The structural features just mentioned are shown (Figs. 8 and 10) and described in detail in my copending application, Ser. No. 347,600, filed July 26, 1940, for improvements in Operating mechanisms for electric switches.

Each switch 20 is also provided with a molded insulating cover member 20^e, of the form shown in greater detail at 79 in Figs. 8 and 10 of my aforementioned application, Serial No. 347,600. Thus each member 20^e is provided with a pair of upwardly opening pivotal bearings (not shown) within which the opposite ends of a pin 29 are adapted to bear, said bearings being so formed as to positively prevent endwise displacement of said pin. Each pin penetrates an opening in and acts as a pivotal support for a switch contactor operating lever 30. The lever 30 of each switch is provided at its lower end with a cam surface 30^a which is adapted in one extreme position thereof to cooperate with cylinder 27 to effect depression of plunger 26, with consequent disengagement of the contactors from the stationary contacts of the switch, as indicated in respect of both switches in Fig. 1. As will be noted, although the two switches 20 are of identical size and construction they are reversely arranged relatively to each other, so that lever 30 of the left-hand switch must move clockwise to effect "off" positioning of its associated contactors, whereas lever 30 of the right-hand switch is moved counterclockwise to effect "off" positioning of its associated contactors.

Levers 30 are normally jointly biased to the respective extreme positions thereof shown in Fig. 1 as by means of a pair of coiled tension springs 31, 31, the opposite looped ends of which are attached to the ends of a pair of pins 32, 32, in the manner best illustrated in Fig. 3. Said pins penetrate openings in and extend a substantial distance on each side of arms or extensions 30^b, 30^b formed integrally with the levers 30, 30, respectively, whereby the aforementioned normally biased movements of said levers are effected.

Levers 30, 30 are also respectively provided with integral angularly extending arms 30^c, 30^c having slightly enlarged ends 30^d, 30^d, which are respectively adapted for interlocking engagement with the end walls of slots 33^a, 33^a formed in the vertical shank portions 33, 33 of like metal members, the horizontal portions 33^b, 33^b of which are rigidly attached to the inner ends of the respective end pushbuttons 34 and 35 of the control station, as by means of self-tapping screws 36, 36 the shanks of which take into preformed recesses in the respective buttons. Said horizontal portions 33^b, 33^b are preferably of rectangular contour, and the same fit into recesses of corresponding width formed in the lower surfaces of the respective pushbuttons 34 and 35 in a substantially flush relationship to said lower surfaces, thus preventing rotation of said pushbuttons relatively to the respective members 33.

Interposed between the head of each screw 36 and its associated portion 33^b of member 33 is a substantially rectangular metal member 37, the purpose of which is to positively limit the degree of upward movement of the respective pushbutton 34 or 35 associated therewith, by engagement of said member with the lower or inner surface of the cover member 16 of the casing. Although the pushbuttons 34 and 35 may be of identical form, they are preferably molded in different molding dies, so that different legends may be formed in the upper surfaces thereof, as, for instance, the respective legends "For," and "Rev.," or the respective legends "Fast" and "Slow," depending upon the particular use to be made of the pushbutton station. In practice, the lettering or legends just mentioned are in the form of depressions in the respective pushbuttons, which depressions are then filled with a suitable enamel of a color contrasting with the color of the material from which the pushbutton is molded, whereby the legibility of the legends is substantially increased.

In practice it is desirable to positively prevent simultaneous depression of pushbuttons 34 and 35 to an extent sufficient to effect completion of the respective circuits to be controlled thereby. Accordingly I provide a pair of relatively long substantially rectangular interlocking links or bars 38, 38 (see Fig. 5), each of which is provided adjacent to the respective ends thereof with a pair of slots 38^a and 38^b of predetermined like lengths through which the aforementioned pins 32, 32 respectively extend. The arrangement is such that when the parts of both switches 20, 20 are in their circuit interrupting positions the pins 32, 32 will be located adjacent to the inner ends of the respective pairs of slots 38^a and 38^b, as shown in Fig. 1. However, upon depression of pushbutton 35 toward its lower extreme position, as shown in Fig. 2, the left-hand pin 32 will first move to the left-hand end of the slots 38^b of members 38, and continued movement of said pin toward the left will result in bodily movement of bars 38, 38 toward the left, until the right-hand ends of slots 38^a, 38^a are closely adjacent to the right-hand pin 32 (Fig. 2).

Such movement of the left-hand pin 32 toward the left away from the right-hand pin 32 will, of course, increase the tension of springs 31, 31. The springs 31, 31 are sufficiently powerful to overcome the resistance to clockwise movement of the lever 30 of the left-hand switch 20 under these conditions, such resistance being due to the action of the switch springs 25 acting through plunger 26 and cylinder 27 upon the 75

cam surface 30^a of the lever, so that upon manual release of said pushbutton 35 (in the absence of any additional elements) the left-hand switch lever would be rotated clockwise from the circuit completing position thereof shown in Fig. 2 to the initial circuit interrupting position thereof shown in Fig. 1, the end 30^d of the arm 30^c of lever 30 acting simultaneously to return pushbutton 35 to its upper extreme position shown in Fig. 1.

As will be apparent from consideration of Fig. 2, due to take-up of the lost motion between the two pins 32 and the two sets of slots 38^a and 38^b the right-hand pushbutton 34 cannot be depressed to a sufficient degree to effect circuit completing operation of its switch mechanism until the parts of the left-hand switch have been moved to circuit interrupting position, such movement also resulting in upper extreme positioning of pushbutton 35.

In like manner, with the aforescribed parts in the respective positions thereof shown in Fig. 1, upon depression of pushbutton 34 to its lower extreme position to effect circuit completing operation of its switch, the right-hand pin will be moved toward the right to first take up the lost motion afforded by slots 38^a, 38^a and continued movement in said direction will effect bodily movement of links 38, 38 to take up the lost motion between slots 38^b, 38^b and the left-hand pin 32. The links 38 thus act to positively insure against circuit completing operation of both switches 20 simultaneously.

With the arrangement thus far described the circuit controlled by each switch 20 would be completed only so long as its associated pushbutton 34 or 35 were held manually in its lower extreme position. In practice it is desirable to insure automatic retention of either of the switches 20 in its circuit closing position as an incident to momentary depression of its associated pushbutton. Accordingly I provide latching means comprising a pair of like flat punched sheet metal members 39, 39 which are arranged in parallel alignment with each other between the aforementioned pair of links 38, 38. The form of members 39 is best illustrated in Fig. 5, and the same are provided at points offset inwardly from the respective ends thereof with upwardly opening notches 39^a and 39^b against the inner vertical walls of which the pins 32 are adapted to abut in the initial position of the switch parts, as shown in Fig. 1. The outwardly extending walls of notches 39^a and 39^b are angled upwardly to a predetermined degree and lead to the vertical walls of notches 39^c and 39^d closely adjacent to the respective ends of said members 39.

Members 39 are provided substantially centrally thereof with circular openings 39^e which are aligned with an opening 40^a in a metal shank member 40 positioned therebetween. A headed rivet 41 loosely penetrates the aligned openings 39^e, 40^a and 39^e and has its shank end upset, as best illustrated in Fig. 3, thus providing a pivotal connection between member 40 and members 39. Shank member 40 has a notched head portion 40^b embedded or molded as an insert within a pushbutton 42, as best illustrated in Fig. 1.

Member 40 has a reduced lower end portion 40^c, thus providing a pair of horizontally aligned shoulders 40^d and 40^e, Fig. 5. Portion 40^c extends downwardly through an opening 19^d (Figs. 1 and 4) in a downwardly offset portion 19^e of flat portion 19^a aforementioned. Surrounding

portion 40^c and interposed between portion 19^e and the notched lower edge portions 39^f of members 39 is a coiled compression spring 43 which acts to bias members 39, member 40 and pushbutton 42 toward their upper extreme positions. As a result of this bias, it will be noted from Fig. 2 that upon counterclockwise movement of the left-hand switch lever 30 (as an incident to depression of pushbutton 35) the left-hand pin will ride out of the left-hand notches 39^b and into alignment with the left-hand notches 39^d of members 39, whereupon spring 43 acts to effect movement of the vertical walls of the last mentioned notches into latching or locking relationship to said left-hand pin 32.

By this arrangement the left-hand switch 20 will be retained in its circuit completing position and pushbutton 35 will also be retained in its depressed position to afford an indication of the condition of the controlled circuit. Also, as will be apparent from Fig. 2, the pushbutton 34 cannot be depressed to effect circuit completing operation of the right-hand switch 20 pending circuit interrupting operation of the left-hand switch 20 with consequent return of pushbutton 35 to its upper extreme position. Such locking of pushbutton 34 against depression thereof is due to the fact that the lost motion between the two pins 32 and the outer end walls of the pairs of slots 38^a, 38^b has been taken up; the left-hand pin 32 abuts against the vertical walls of the pair of notches 39^d, whereas the pushbutton 42 and its shank member are substantially limited to reciprocating movement in a vertical plane, thus preventing any substantial degree of displacement of pivot pin 41 out of said vertical plane.

However, upon momentary depression of pushbutton 42 the vertical walls of the pair of notches 39^d will be moved downwardly out of the plane of travel of the left-hand pin 32, so that the latter is freed to move toward the right (under the bias of springs 31) to the position thereof shown in Fig. 1, the lever 30 of the left-hand switch 20 being simultaneously rotated by said springs to return said switch to its normal circuit interrupting position shown in Fig. 1. Thereafter either pushbutton 35 or 34 may be depressed to effect circuit completing operation of its associated switch, it being understood that such switch will be automatically latched in circuit completing position and that the other pushbutton be positively restrained against depression pending momentary depression of the "stop" pushbutton 42, as aforescribed.

If the control station illustrated in Figs. 1 to 5 is utilized for reversing control of a motor, the end button 35 may have the legend "For." applied thereto; the other end button 34 may carry the legend "Rev.", the intermediate button 42 being marked "Stop." On the other hand, if the control station is used in conjunction with a two-speed motor the buttons 35 and 34 may be marked "Fast" and "Slow," respectively; the button 42 carrying the legend "Stop." The three-pole switch illustrated in Figs. 1 to 5 has a rating of two horsepower in the control of a polyphase motor, at 440 to 550 volts.

The switches 20 of Figs. 1 to 5 are rigidly secured to the aforementioned flat portion 19^a of bracket 19 as by means of their respective pairs of diagonally arranged securing screws, one screw, 19^f and 19^g, of each of the respective pairs being illustrated in Fig. 3. As shown in Fig. 1, the downwardly offset portion 19^e has ends 19^h and

19ⁱ of approximately semicircular form to fit within vertical grooves 20^f, 20^g of corresponding form in horizontal cross section provided in the adjacent ends of the insulating cover members 5 20^e of switches 20. In like manner, portion 19^h is provided with downwardly angled integral lugs (one of which is shown at 19^j at the left-hand end of Fig. 1) to fit within the like grooves 20^f at the respective outer ends of said cover members. Such engagement of the lugs and grooves just mentioned serves to insure positive tandem alignment of the two switches 20 with respect to each other when the parts are completely assembled.

15 With reference to Figs. 1 and 5, it is to be understood that the three terminal screws 23 at the outer ends of the respective switches 20 are adapted for attachment of circuit wires, whereas the longitudinally aligned terminal screws 23 at 20 the adjacent ends of switches 20 are electrically connected with each other, as by means of three like plates or bus members 44. It is accordingly only necessary to attach circuit wires by 25 one of the two screws 23 associated with each bus bar 44 to provide the proper electrical connections common to the two switches 20. Bus members 44 are employed in both the reversing and two-speed control types of pushbutton stations. Other wiring arrangements for the switch 30 mechanisms may, of course, be employed if desired.

The three pushbutton reversing and/or two-speed motor control station illustrated in Figs. 35 6, 7 and 8 is functionally and operatively similar to that aforescribed, but is modified in respect of certain structural details to provide for use of two like double-pole snap switches of the character disclosed and claimed in my prior patents, No. 1,889,259, granted Nov. 29, 1932, and No. 40 1,977,078, granted Oct. 16, 1934.

Thus the switches 50 and 51 may be identical with each other in all respects, but the same are reversely arranged in tandem or end-to-end relationship with each other when mounted upon the flat portion 52^a of a yoke or bracket 52, the ends of which bracket are rigidly secured to the inner surface of the aforescribed cover member 16, a fragment of which is shown in Figs. 6 and 7. Portion 52^a of the bracket is located 45 in inwardly offset parallel relationship to the cover member 16 and the switches 50 and 51 are each rigidly attached thereto, as by means of a pair of screws 53, 53, in the manner best illustrated at the left-hand end of Fig. 6.

55 Each switch 50 and 51 comprises a molded insulating base 54, a flat punched insulating cover member 55, and a punched and stamped sheet metal cover member 56 to which a metal bushing 57 is rigidly attached. The initially closed upper end of each bushing is provided with a kerf 57^a (as shown at the left-hand end of Fig. 6) to provide oscillatory clearance for the three arms 58^a, 58^b and 58^c of a lever which is pivotally connected with the bushing, as by means of a pin 59. The arm 58^a of each lever extends downwardly through the bushing for cooperation with the snap actuating elements of the switch, as 60 disclosed in my prior patents aforescribed. The arm 58^b of each lever is provided adjacent to its free end with an opening 58^d which is substantially larger in diameter than the pin 60 which extends therethrough.

Each pin 60 is headed and the shank thereof 70 passes transversely through openings provided 75 in the parallel downward extensions 61^a and 61^b

of a pushbutton 61, each lever arm 58^b being positioned between said extensions. Positioned within a suitable cavity in each pushbutton 61 and adapted to press downwardly at all times against the end of arm 58^b is a coiled compression spring 62, which also acts to at all times bias the pushbutton 61 upwardly to a predetermined degree relatively to the lever arm 58^b. This arrangement provides the necessary amount of lost motion between pin 60 and lever arm 58^b and at the same time avoids any undesirable looseness or rattling of the pushbutton 61. Cover member 16 is provided with upstanding cylindrical flanges 16^a and 16^b to assist in limiting the pushbuttons 61 to reciprocating movement in a straight line.

The arms 58^c of the respective levers are provided in their ends with openings through which the pair of pins 32 aforescribed are adapted to pass, said pins also extending through longitudinally extending slots 63^a and 63^b in a pair of like elongated rectangular members 63 (only one of which is shown in Figs. 6 and 7), said members 63 being structurally equivalent to the members 38 aforescribed.

Positioned between members 63 are a pair of like latch members 64, only one of which is visible in Figs. 6 and 7. The form of members 64 is best illustrated in Fig. 8, the same being functionally like and structurally similar to the members 39 aforescribed. Positioned between the pair of members 64 is the metal shank 65, which has its upper end (not shown) embedded or molded in the center pushbutton 66. A headed pin 67 has its shank penetrating alined openings 64^e (Fig. 8) in members 64 and in shank 65 to pivotally connect said three members to each other.

Members 64 are provided adjacent opposite ends thereof with notches or cut-away portions producing vertical shoulders 64^a and 64^b against which the pins 32, 32 are drawn by the pair of tension springs 31 (see Fig. 6) when both switches 59 and 51 are in circuit interrupting position, as shown in Fig. 6. Members 64 are also notched at points more closely adjacent their opposite ends to provide vertical shoulders 64^d and 64^c to alternately cooperate with the ends of the respective pins 31 when the right-hand or left-hand pushbutton 61 is depressed, as illustrated by the depressed position of the right-hand pushbutton in Fig. 7. Cover member 16 is provided with an upstanding circular flange 16^c to assist in guiding pushbutton 66 and limiting the same to reciprocating movement in a straight line.

With the right-hand switch 51 in circuit completing position as shown in Fig. 7 the left-hand pushbutton 61 cannot be depressed to effect simultaneous circuit completing positioning of the left hand switch 50, the opposite ends of the right-hand pin 32 cooperating with the shoulders 64^d on latch members 64 to prevent such movement of the parts. As will be noted the reduced lower end of the shank 65 extends downwardly through a flanged opening 52^b in member 52 to prevent any substantial degree of lateral displacement of said shank; a coiled compression spring 68 of substantially frusto-conical form having its enlarged lower end seated against the flat portion 52^a around opening 52^b and having its reduced upper end engaged with shoulders 65^b and 65^c formed by reduced portion 65^a. Here, as in the device of Figs. 1 to 5, however, upon momentary depression of the center pushbutton 66 against the upward bias of spring 68 the shoul-

ders 64^d will be displaced downwardly out of engagement with right-hand pin 31 which is then drawn by springs 31 to its normal position shown in Fig. 6, with consequent interruption of the circuit controlled by the right-hand switch 51. Thereafter either the left-hand or right-hand pushbutton 61 may be depressed, and latched automatically in depressed position, to effect closure of the circuit controlled by its respectively associated switch 50 or 51.

The usual end wiring terminals 69 of the switches have associated therewith the substantially L-shaped members 69^b and 69^c, and attached to said terminals by screws 69^a, the members 69^c having portions underlying portions of the members 69^b between the two switches, whereby six bottom-wiring binding screws 23 of usual form may be associated with the two switches.

20 Bracket 52 is permanently attached to the inner surface of cover member 16 as by means of a pair of metal eyelets 18, 18. In practice the flat portion 52^a of bracket 52 is provided with longitudinally extending ribs 52^c adjacent opposite edges thereof to increase the strength and to resist transverse bending or deformation thereof. The center pushbutton 66 is preferably provided with the legend "Stop" and the end pushbuttons 61, 61 are provided with alternative legends, as described in connection with Figs. 1 to 5, according to the particular character of control functions contemplated. The switch illustrated in Figs. 6 to 8 has a rated capacity of one-half horsepower at 115 or 230 volts, direct current.

The modified form of pushbutton control station illustrated in Fig. 8^a is in many respects like that of Figs. 6 to 8, and certain parts identical with those of Figs. 6 to 8 may be employed, the same saving being given like numerals of reference. The device of Fig. 8^a may be operated to perform the same functions as the device of Figs. 6 to 8; and in addition the same is so constructed as to provide for alternate depression of the end pushbuttons 61, 61, subsequent to depression of one of the latter, without necessitating momentary depression of the center pushbutton 70, which in this device is of special form.

More particularly, the pushbutton 70 is provided at its lower end with an annular flange 70^a which is adapted to underlie the inner surface of the cover member 16, to limit the degree of outward displacement of said pushbutton. Pushbutton 70 is provided with a recess 70^b opening 55 to its lower end, said recess being of a width (transversely with respect to cover member 16) which is only slightly greater than the thickness of a metal member 71 whose upper end portion is at all times positioned within said recess. Recess 70^b has a dimension (longitudinally with respect to cover member 16) which is substantially greater than the width of that portion of member 71 which projects upwardly thereinto; thus providing for a predetermined degree of oscillatory movement of member 71 with respect to said pushbutton 70. Recess 70^b extends upwardly beyond the upper end of member 71 to such a degree as to permit depression of pushbutton 70 at any time without interference by the member 71.

Member 71 is pivotally connected to a pair of latch members 64 (which are preferably identical with the corresponding members described in connection with Figs. 6 to 8) as by means of

the pivot pin 67 aforescribed. Positioned on opposite sides of members 64 are a pair of members (one of which is illustrated and designated by the numeral 63^x). The members 63^x are substantially identical in form with the members 63 described in connection with Figs. 6 to 8; but each member 63^x is provided in its upper edge with a notch 63^y, the purpose of which is to provide for downward or unlatching movement of the pair of members 64 without interference by the members 63^x, as will be obvious.

As will be noted from Fig. 8^a, the other parts of the control station (including the various elements of the two switches, not illustrated) correspond with those illustrated in Fig. 7. The parts of the control station of Fig. 8^a function in the manner described in connection with Figs. 6 to 8 to prevent simultaneous depression of the end pushbuttons 61, 61, whereby circuit completing operation of both switches simultaneously is positively prevented.

On the other hand, after circuit completing positioning of the corresponding switch by depression and latching of the lower pushbutton 61, it will be apparent that upon subsequent depression of the upper pushbutton 61 the elements will function to effect interruption of circuit by the switch associated with the lower pushbutton 61, with consequent return of the lower pushbutton 61 to its upper extreme position, and thereafter the switch associated with the upper pushbutton 61 of the station will be operated to its circuit completing position, the upper pushbutton 61 being retained in its fully depressed position. Under these conditions, it is to be noted that the lower pin 32 will be maintained in engagement with the walls 64^d of the end notches of members 64, and the retention of the parts in the respective positions thereof last mentioned will result from application of the force of spring 68 to pivot pin 67 at an angle upwardly with respect to the horizontal center line of pushbutton 70, as shown in said Fig. 8^a, the member 71 having been swung or oscillated to the position thereof shown in dotted lines at 71^a under these conditions.

On the other hand, regardless of whether the lower or upper pushbutton 61 is depressed the same may be unlatched for return thereof to its upper extreme position, with consequent interruption of the circuit controlled by its respective switch, by momentarily depressing the center pushbutton 70.

Assuming that both of the end pushbuttons 61, 61 are in their respective upper extreme positions; if the upper pushbutton 61 is depressed, the upper pin 32 will be drawn upwardly against the bias of the pair of springs (31, not shown in Fig. 8^a) until the walls of end notches 64^c of members 64 are free to move into latching engagement with the ends of said pin, under the bias of spring 68, thus effecting retention of the switch associated with the upper pushbutton 61 of the station in circuit completing position. If the lower pushbutton 61 is then depressed, prior to momentary depression of the center pushbutton 70, the members 64 will be maintained in latching relationship to the upper pin 32, but the members 63^x and 64 will be moved bodily downward to effect circuit interruption by the switch associated with the upper pushbutton 61 and subsequent completion of circuit by the switch associated with the lower pushbutton 61, the member 71 being tilted to the position thereof shown at 71^b, whereby the spring 68 will act

to maintain the switch parts in the various positions thereof last mentioned.

The relationship of the recess 70^b in pushbutton 70 to the member 71 is such that rotation of pushbutton 70 is positively prevented, thus insuring proper positioning of the legend (such as "Stop") which may be applied thereto.

The pushbutton station illustrated in Fig. 8^a is of advantage in those installations wherein it is desirable to provide for reversal of a controlled motor by plugging; inasmuch as the reverse circuit connections may be completed almost simultaneously with the moment of interruption of the circuit connections previously obtaining.

The three pushbutton control station illustrated in Figs. 9 to 12 is adapted to employ certain parts identical with those illustrated in Figs. 6 to 8, and such parts have been given like numerals of reference. On the other hand, the device of Figs. 9 to 12 is adapted for performance of the additional function described in connection with Fig. 8^a; namely, enabling depression of the end pushbuttons 61, 61 alternately to effect the required operation of both switches, without necessitating operation of the center pushbutton 66^a in each instance. Here, as in Fig. 8^a, however, the center pushbutton 66^a may be momentarily depressed after depression of either of the end pushbuttons 61, 61 to insure upper extreme positioning of both of the latter, with consequent interruption of both of the circuits controlled by the respective switches.

The two switches 75 and 76 are preferably of like form, and are mounted in reverse relationship to each other (in respect of their operating levers 77 and 78 as by means of pairs of eyelets 79, 79) to the flat portion 52^a of the supporting bracket 52. Each of the switches 75 and 76 is of the double-throw type, without an intermediate "off" position, and the same may be assumed to be of the three-pole type. Switches of this character are disclosed in the copending application of Alvin W. Krieger, filed Nov. 16, 1940, Serial No. 365,907, attention being particularly invited to Fig. 5 of the drawings of said Krieger application. It is to be understood, of course, that the switches 75 and 76 may be modified (by omission of one or two sets of stationary and movable contact members) to selectively provide switches of the two-pole or single-pole type.

As will be understood from consideration of Fig. 10, the arrangement is such that with both end pushbuttons 61, 61 in their upper extreme positions the three tiltable contactors (one of which is shown at 80 in Fig. 10) of each switch are engaged with the outer stationary contacts, one of which is shown at 81. In practice the switches 75 and 76 will be so wired as to provide, under the conditions just mentioned, for interruption of both the "Forward" and "Reverse" circuits, or the "Fast" and "Slow" speed circuits of the controlled motor, according to the characteristics of the particular installation.

If the left-hand end button 61 is then depressed (as shown in Fig. 11) the three contactors 80 of the left-hand switch 75 will be tilted into engagement with the inner stationary contacts of said switch, one of said contacts being shown at 82, the contactors of the other switch 76 remaining in engagement with their outer stationary contacts (not shown). This may be assumed to provide for either "Forward" or "Fast" speed operation of the controlled motor (according to the particular installation).

The left-hand pushbutton 61 will be retained

in its depressed position and the right-hand pushbutton 61 will be held in its upper extreme position by the action of a pair of like combined interlocking and latching members 83, 83, one of which is shown in detail in Fig. 9. As shown, members 83 are each provided at the right-hand end thereof with a circular opening to freely accommodate the right-hand pin 32. Said members are each further provided at the other end thereof with a substantially L-shaped slot, whose horizontal portion is designated 83^b and whose vertical downwardly extending portion is designated 83^c. The slots in members 83 are adapted to accommodate the left-hand pin 32. Pins 32 are respectively pivotally connected with the arms 77^a and 78^a of levers 77 and 78, the springs 31, 31 biasing said pins, said levers and their associated parts to the relative positions thereof shown in Fig. 10.

With the parts in the respective positions thereof shown in Fig. 10, upon depression of left-hand pushbutton 61 the left-hand pin 32 will be drawn toward the left along portion 83^b of each slot until it registers with the vertical portions 83^c of said slots, whereupon the spring 68 in its upward bias against pin 85, which is in turn engaged with the lower edges of members 83, causes upward tilting of members 83 to the position thereof shown in Fig. 11. This latching action results in interlocking the two end pushbuttons 61, 61 to positively restrain the same against movement independently of each other. Similarly, with the parts as shown in Fig. 10, the same interlocking action would result from depression of the right-hand pushbutton switch 61, inasmuch as the right-hand pin 32 would draw the members 83 bodily toward the right until the vertical portions 83^c of the notches were free to move upwardly, under the bias of spring 68, to effect the interlocking engagement aforementioned.

As will be understood, such interlocking engagement of the vertical portion 83^c of the slots with the left-hand pin 32 will be maintained (see Fig. 11) during subsequent depression of the end pushbuttons 61, 61 alternately, so that mere depression of that pushbutton 61 which happens to be in its upper extreme position will effect interruption of the circuit which is then completed and substantially simultaneously effect completion of the circuit which is then interrupted. On the other hand, if either of the circuits has been completed by depression of one or the other of the pushbuttons 61, 61, the same may be interrupted at any time (thus insuring interruption of both circuits) by momentarily depressing the center pushbutton 66^a, which results in depression of members 83 to effect disengagement of the vertical portions 83^c of the slots from the left-hand pin 32, whereupon the springs 31 will act to bring that pin 32 which has been last moved to the normal position thereof shown in Fig. 10.

Pin 85 is attached by a drive fit (see Fig. 12) within an opening in a shank member 86, the upper end of which is molded or embedded within the body of center pushbutton 66^a.

As shown, the levers 77 and 78 are pivotally attached to pairs of brackets 87, 87, as by means of pivot pins 88, said brackets being in turn attached to the metal cover plates 89 of the switches. The lower ends of levers 77 and 78 are forked, as shown at 77^b and 78^b, for cooperation with the oscillatable insulating actuating members of the switches, one of which members is shown at 90 in Fig. 10. The operation of the other ele-

ments of switches 75 and 76 is believed to be apparent, attention being invited to the aforementioned Krieger application, Ser. No. 365,907, for a detailed description of such switches. Although I have shown the switches 75 and 76 equipped with solder type terminal members 91 and 92, it is to be understood that other forms of wiring terminal elements may be employed if desired.

It is to be understood that all of the switches herein disclosed are adapted for enclosure within a casing of the aforescribed character comprising the main body portion 15 and the cover member 16.

Although I prefer to employ duplicate interlocking links 38, 38 and duplicate latching bars 39, 39 in the device of Figs. 1 to 5, and similar duplicate interlocking and latching elements in the other devices illustrated, it will be apparent to those skilled in the art that satisfactory results may be obtained by employment of single elements of the character illustrated, in which case the respective elements would preferably be formed from sheet metal of substantially greater thicknesses than those illustrated.

What I claim as new and desire to secure by Letters Patent is:

1. As an article of manufacture, a manually operable switch assembly of the pushbutton type comprising, a metal supporting member having a substantially flat portion, a pair of multi-pole switches of like form secured to said flat portion, each of said switches having a pivoted operating lever extending forwardly beyond the front face of said flat portion, a pushbutton pivotally connected with each lever in offset relation to the point of pivotal support of the latter, means comprising a coiled tension spring having its opposite ends attached to said levers at points offset from the points of pivotal support thereof to normally bias each of said pushbuttons to a given extreme position forwardly of the front face of said flat portion, means comprising a metal member pivotally attached to each of said levers to positively prevent simultaneous depression of said pushbuttons to their inner extreme positions, means including a pivotally supported and spring-biased latch member operable automatically to retain either of said pushbuttons in its inner extreme position when depressed, a third pushbutton pivotally attached to said latch member whereby the former is normally biased to its outer extreme position, said third pushbutton being adapted when depressed to effect release of either of said other pushbuttons for movement of the latter under the bias of said tension spring to the forward extreme position thereof, for the purpose set forth, and a cover member attached to said supporting member in a plane parallel to and spaced forwardly from the latter and adapted to conceal all of the switch parts except the cylindrical upper end portions of said pushbuttons, said cover member having openings formed therein to accommodate said cylindrical upper end portions of the respective pushbuttons and to restrict at least the two first mentioned pushbuttons to reciprocatory movement in a substantially straight line.

2. As an article of manufacture, a manually operable switch assembly of the pushbutton type comprising, a supporting member having a substantially flat portion, a pair of switches of like form secured to said flat portion, each of said switches having a pivoted operating lever extending forwardly beyond the forward face of said

flat portion, a pushbutton pivotally connected with each lever in offset relation to the point of pivotal support of the latter, spring means associated with said pushbuttons to normally bias each of the same to a given extreme position forwardly of the front face of said flat portion, means comprising at least one tie member having a pivoted lost motion connection with each of said levers to positively prevent simultaneous depression of said pushbuttons to their inner extreme positions, and means comprising at least one spring biased latch member common to said levers and operable automatically to retain either of said pushbuttons in its inner extreme position.

3. As an article of manufacture, a manually operable switch assembly of the pushbutton type comprising, a supporting member having a substantially flat portion, a pair of switches of like form secured to said flat portion, each of said switches having a pivoted operating lever extending forwardly beyond the forward face of said flat portion, a pushbutton pivotally connected with each lever in offset relation to the point of pivotal support of the latter, spring means associated with said pushbuttons to normally bias each of the same to a given extreme position forwardly of the front face of said flat portion, means comprising at least one tie member having a pivoted lost motion connection with each of said levers to positively prevent simultaneous depression of said pushbuttons to their inner extreme positions, means comprising at least one spring biased latch member common to said levers and operable automatically to retain either of said pushbuttons in its inner extreme position, and means comprising a third pushbutton operatively connected with said latch member intermediate the ends of the latter, said last mentioned pushbutton when manually depressed being adapted to render said latch member ineffective with respect to either of said levers.

4. As an article of manufacture, a manually operable switch assembly of the pushbutton type comprising, a supporting member having a substantially flat portion, a pair of switches of like form secured to said flat portion, each of said switches having a pivoted operating lever extending forwardly beyond the forward face of said flat portion, a pushbutton pivotally connected with each lever in offset relation to the point of pivotal support of the latter, spring means associated with said pushbuttons to normally bias each of the same to a given extreme position forwardly of the front face of said flat portion, means comprising at least one tie member having a pivoted lost motion connection with each of said levers to positively prevent simultaneous depression of said pushbuttons to their inner extreme positions, means comprising at least one spring biased latch member common to said levers and operable automatically to retain either of said pushbuttons in its inner extreme position, means comprising a third pushbutton having a pivoted driving connection with said latch member intermediate the ends of the latter, whereby said last mentioned pushbutton is normally held in its forward extreme position under the bias of said latch member, and said last mentioned pushbutton when manually depressed being adapted to momentarily render said latch member ineffective to retain either of said first mentioned pushbuttons in its inner extreme position.

5. In a motor control station of the pushbutton type, in combination, an enclosing casing comprising a recessed body member and a cover

member, a metal bracket secured to the inner surface of said cover member and having a flat portion spaced inwardly from and parallel to said inner surface, a pair of electric switches of like construction attached to the inner surface of said flat portion, each of said switches including a pivoted operating lever at least a portion of which is located between the outer surface of said flat portion and said cover member, a single pushbutton pivotally connected with each of the respective levers in offset relation to the point of pivotal support of the latter, spring means associated with said pushbuttons to normally bias each of the same to its outer extreme position, means including a link having a lost motion connection with each of said levers while positively insuring against simultaneous depression of said pushbuttons to their respective inner extreme positions, means including a spring-biased latch common to said levers and operable automatically to effect retention of either of said pushbuttons in its inner extreme position, a third pushbutton adapted when depressed momentarily to effect release of either of the first mentioned pushbuttons retained thereby, said cover member having openings formed therein to accommodate said three pushbuttons and to limit the two pushbuttons first mentioned to reciprocating movement in a straight line, and means for rigidly but removably attaching said cover member to said body member.

6. In a motor control station of the pushbutton type, in combination, an enclosing casing comprising a recessed body member and a cover member, a metal bracket secured to the inner surface of said cover member and having a flat portion spaced inwardly from and parallel to said inner surface, a pair of electric switches of like construction attached to the inner surface of said flat portion, each of said switches including a pivoted operating lever at least a portion of which is located between the outer surface of said flat portion and said cover member, a single pushbutton pivotally connected with each of the respective levers in offset relation to the point of pivotal support of the latter, spring means associated with said pushbuttons to normally bias each of the same to its outer extreme position, means including a link having a lost motion connection with each of said levers while positively insuring against simultaneous depression of said pushbuttons to their respective inner extreme positions, means including a spring-biased latch common to said levers and operable automatically to effect retention of either of said pushbuttons in its inner extreme position, a third pushbutton adapted when depressed momentarily to effect release of either of the first mentioned pushbuttons retained thereby, said cover member having openings formed therein to accommodate said three pushbuttons and to limit all of said three pushbuttons to reciprocating movement in a straight line, and means for rigidly but removably attaching said cover member to said body member.

7. In a pushbutton operated switch mechanism, a first pushbutton, a pivoted switch lever having an operative connection therewith, a set of contacts adapted to be closed upon pivotal movement of said lever as an incident to depression of said pushbutton to effect completion of an electric circuit, a second pushbutton, a second pivoted switch lever having an operative connection with the latter, a second set of contacts adapted to be closed upon pivotal movement of said last

mentioned lever as an incident to depression of said second pushbutton to effect completion of a different electric circuit, means including a metal member mechanically connected to said levers jointly to positively restrain said pushbuttons against depression thereof simultaneously to thereby insure against completion of more than one of said electric circuits at a time, spring means common to said levers and said pushbuttons to normally bias the latter jointly toward their upper extreme positions, thereby tending to interrupt both of said electric circuits, means including a spring-biased latch-bar common to said levers and said pushbuttons to latch each of the latter in its lower extreme position when depressed selectively, and means comprising a third pushbutton positioned between and in parallel relationship to the other pushbuttons, said third pushbutton being associated with said spring biased latch-bar and adapted when momentarily depressed to effect unlatching of said first or second pushbutton if depressed, whereby both of said electric circuits are interrupted, said third pushbutton and its associated parts comprising the sole means for controlling and effecting interruption of either of said electric circuits when completed.

8. As an article of manufacture, a manually operable switch assembly of the pushbutton type comprising, a substantially flat supporting member, switch mechanism secured to said supporting member, actuating means for said switch mechanism comprising a pair of pivoted levers and opposite end pushbuttons having positive driving connections therewith respectively, a third pushbutton positioned between and in parallel relationship to said end pushbuttons, spring means common to said end pushbuttons to normally bias each of the same to a given position forwardly of the front face of said supporting member, means including a metal tie-bar mechanically connected to said levers to positively prevent simultaneous

- depression of said end pushbuttons to their inner extreme positions, and spring-biased means including a latch-bar common to said levers and operable automatically to retain either of said end pushbuttons in its inner extreme position when depressed, said last mentioned means also acting to normally bias said third pushbutton to a given position forwardly of the front face of said supporting member.
9. As an article of manufacture, a manually operable switch assembly of the pushbutton type comprising, a substantially flat supporting member, switch mechanism secured to said supporting member, actuating means for said switch mechanism comprising a pair of pivoted levers and opposite end pushbuttons having positive driving connections therewith respectively, a third pushbutton positioned between and in parallel relationship to said end pushbuttons, spring means common to said end pushbuttons to normally bias each of the same to a given position forwardly of the front face of said supporting member, means including a metal tie-bar mechanically connected to said levers to positively prevent simultaneous depression of said end pushbuttons to their inner extreme positions, spring-biased means including a metal latch-bar common to said levers and operable automatically to retain either of said end pushbuttons in its inner extreme position when depressed, means including a pivotal connection between said latch-bar and said third pushbutton whereby upon momentary depression of the latter either of said end pushbuttons is released for automatic return to the aforementioned normally biased position thereof, and means including said pivotal connection between said third pushbutton and said latch-bar to positively prevent depression of one of said end pushbuttons after depression of the other of the same pending momentary depression of said third pushbutton, for the purpose set forth.

GEORGE J. MEUER.
